UNITED STATES PATENT OFFICE.

FRANK B. MULFORD, OF ST. LOUIS, MISSOURI, AND JOHN DAVID DICKINSON, OF CHICAGO, ILLINOIS; SAID DICKINSON ASSIGNOR TO SAID MULFORD.

COMPUTING MECHANISM.

Application filed February 19, 1921. Serial No. 446,517.

To all whom it may concern:

Be it known that we, FRANK B. MULFORD and JOHN DAVID DICKINSON, citizens of the United States, residing, respectively, at St. Louis, in the county of St. Louis and State of Missouri, and Chicago, in the county of Cook and State of Illinois, have invented a certain new and useful Improvement in Computing Mechanism, of which the following is full, clear, concise, and exact description, reference being had to the accompanying drawings, forming a part of this specification.

Our invention relates to improvements in computing mechanism, and it is particularly concerned with the provision of a new and improved computing mechanism for determining the proper postage to be applied to a package to be mailed to a destination located in any given postal zone. While this is the principal object of our invention, it is not limited to this use, but may be used for computing other values depending upon two variable quantities.

25 The objects of our invention are:

First: To provide a computing mechanism for determining values which are dependent upon two variable quantities.

Second: To provide a mechanism of the character described comprising means for printing the result of each determination.

Third: To provide mechanism of the character described by which the computing value is printed upon a medium which can be attached to a package or other article.

Fourth: To provide a member having a plurality of rows or series of type figures, wherein the values of the numbers in each row or series progressively increase, means for co-acting with the type figures for producing a printed impression upon a suitable medium, preferably a paper strip, and means for positioning said member and its co-acting means controlled by a weighing mechanism or some other mechanism which is actuated in accordance with a second variable quantity.

Fifth: To provide a computing mechanism of the character described, wherein a weighing mechanism is employed for determining the position of the members for

making the printed impressions upon the receptive medium.

Sixth: To provide a computing mechanism comprising a weighing mechanism and means for indicating a value proportional to the weight of the object weighed.

Seventh: To provide a computing mechanism comprising means for making a printed impression proportional in value to the weight of an object, and

Finally: To provide a mechanism of the character described which is simple in construction, economical to manufacture, rugged, and easy to operate.

Other objects will appear as this description progresses, reference being had to the accompanying drawings, in which—

Figure 1 is an end elevation of the mechanism embodying our invention.

Figure 2 is a longitudinal section taken substantially on the line 2—2 of Figure 1.

Figures 3, 4 and 5 are vertical transverse sections taken on lines 3—3, 4—4 and 5—5 respectively of Figure 2.

Figure 6 is an enlarged sectional detail taken on line 6—6 of Figure 5.

Figure 7 is a longitudinal substantially horizontal section taken on line 7—7 of Figure 2, portions of the apparatus being shown in elevation.

Figure 8 is a vertical longitudinal sectional detail taken on line 8—8 of Figure 1, and

Figure 9 is a fragmentary plan view of the drum forming a portion of our invention.

Throughout the several views, similar reference characters will refer to similar parts, and the sections are taken looking in the directions indicated by the small arrows.

Referring to the drawings, our improved computing mechanism comprises a cylindrical drum 10, the periphery of which supports a plurality of rows 11 of type figures, the figures of each row of which are arranged in ascending values corresponding to the postal charges for a given zone. As shown in Figure 9, the zero positions of all of these rows lie in a line extending longitudinally of the drum, and substantially parallel with the axis thereof. For the

sake of clearness, the type in this view have been reversed so as to read as the impressions would be printed. The drum 10 is provided with two end plates, 12 and 13, respectively, the first of which is provided with a hub 14 to which is secured by means of the pin 15 one end of a shaft 16. The opposite end of the shaft 16 is rotatably mounted in a bearing 17, which is supported by the pedestal 18. The pedestal 18 is in turn secured to a flange 19, extending upwardly from the base casting of the machine by means of screws 20, or in any other suitable manner. The opposite end plate 13 is provided with a hub 21, which is journaled upon a sleeve 22. The outer end of the sleeve 22 is secured in a bore in the upper end of the pedestal 23 by means of a set screw 24, which prevents the sleeve from rotating. The pedestal 23 is removably secured to the upstanding flange 25 forming a part of the base casting by means of a screw 26.

For rotating the drum 10 upon the supports just described, we provide a spiral spring 28, the inner end of which is secured to a sleeve 29, which, in turn, is rigidly secured to the sleeve 22 by means of the key 30. The opposite end of the spring is secured to a sheet metal drum 31 by having its end wrapped about the pin 32, one end of which extends through a projecting ear 33 forming a part of the drum, and the other end of which extends through the end 34 of the drum as shown at 35. An internal gear 36 is secured to the drum 31 by means of the flange 37, which is formed integral with said gear. This gear meshes with a pinion 38 rigidly secured to one end of the shaft 39. The opposite end of the shaft 39 has a gear 40 rigidly secured thereto, which meshes with a pinion 41, which in turn is rigidly secured to a shaft 42, to the outer end of which is secured a large spur gear 43. The spur gear 43 drives a pinion 44, which is rigidly secured to the shaft 45. The outer end of the shaft 45 has a spur gear 46 rigidly secured thereto, which meshes with the internal gear 47, which is suitably secured to the inner wall of the drum 10. The gearing just described forms a multiplying gear system connecting the spring 28 in driving relation with the drum 10, and since, as it will appear, the drum 10 requires but very little power for rotating it, one winding of the spring 28 will serve to drive the drum 10 through a large number of complete revolutions.

For a purpose which will later appear, we prefer to provide means for controlling the speed of revolution of the drum 10, and for this purpose we provide an air vane 50, which is secured to one end of the shaft 51. The shaft 51 is connected to the gear 46 by a pinion 52 (Fig. 5) in such manner that when the drum is rotated the

vane 50 will rotate at comparatively high speed, thereby setting up a resistance tending to slow down the movement of the drum. The shafts 39, 42, 45 and 51 all find suitable bearings in the plate 55, which is rigidly secured to the inner end of the winding stem 57 by a screw 56, which is rotatably mounted in the sleeve 22, and the outer end of which projects through an opening 58 in the cover plate 59, and is provided with a suitable handle 60 by means of which it can be rotated to wind the spring in a manner which will be described later on. To prevent backward rotation of the stem 57 we secure a ratchet 61 thereto, which is engaged by a suitable pawl 62 pivotally mounted upon the pedestal 23 by means of a screw 63. The ratchet is held upon the stem 57 by means of a nut 64.

In the embodiment of our invention disclosed herein, the spring 28 is wound in such direction that during the operation of our machine the upper side of the drum in Figure 2 rotates away from the observer. To wind the spring, the handle 60 is turned in the opposite direction, thereby carrying the plate 55 and the various shafts and gears mounted thereon with it in the same direction. During the winding operation, the drum is held stationary by means of a spring-pressed pawl 65, which is pivotally mounted upon the upper end of the pedestal 23, and which engages suitably formed ratchet teeth 66 on the hub of the end plate 13 to prevent the drum from rotating in the direction in which the handle 60 is being turned.

We shall now describe the means which co-act with the type of the various rows of type figures to make printed impressions upon paper ribbons, one side of which are gummed so that they can be secured to the packages weighed. Referring for the present to Figures 2 and 5, a transversely curved supporting plate 70 is supported above the drum 10 by means of the up-turned flanges 71 and 72, which are respectively secured to the housing by the screws 73 and 74. A plurality of shallow grooves 75 extend transversely of the upper surface of the plate 70 for receiving the paper ribbons R. The ribbons are held in the slots 75 by means of a second plate 76, the lower side of which conforms to the curvature of the plate 70. The plate 76 is carried by the downwardly projecting flanges 78 and 79 of the cover plate 80, which forms a part of the housing, and which is pivotally mounted upon the pintle 81. The ends of the pintle 81 are supported by the lugs 82 and 83 projecting from the adjacent stationary portions of the housing.

A stationary shaft 85 has its opposite ends secured in and supported by the flanges 78 and 79 of the cover plate, and extends

just above and parallel with the plate 76. A plurality of levers 86 are rotatably supported side by side upon the shaft 85, there being one of these levers for each of the 5 ribbons R. At their forward ends, these levers each support a platen 87, and a key 88. The platens 87 are adapted to co-operate with the type of the corresponding rows 11 to make impressions upon the associated paper strips R. A spring 89 coiled 10 around the hub of each of the levers 86, and having one end in engagement with the cover, and the other pressing against the lower side of the lever, provides means for holding the lever in its normal or retracted 15 position. The keys 88 are each provided with a character indicating one of the postal zones.

It is possible to make the type of the 20 rows 11 of such character as to make perforated impressions in the paper ribbons, but we prefer to provide means for making inked impressions, and for this purpose we provide the inking ribbon I, (see 25 Figs. 1, 3, 4, 5, 6, and 7) which is supplied from a spool 90, which is rotatably mounted upon a pivot pin 91 shown in Figure 7, and passes downwardly and beneath and then horizontally between the paper 30 ribbons R and the bars 92 formed by the apertures 93 in the plate 76, through which the platens 87 are adapted to pass. A take-up spool 95 is rotatably mounted upon the pin 96, which is supported from the casing 35 by a suitable bracket 97. A worm gear 98 is secured to one side of the spool 95, and is adapted to be engaged by the spiral thread 99 formed on the outer end of the drum 10. The pitch of the thread 99 is 40 such that the gear 98 will be advanced one tooth for each revolution of the drum 10. In this manner, the inking ribbon I will be advanced a distance proportional to the pitch of the gear 98 thereby insuring a 45 new inking surface for each impression made by the platens 87, although it will, of course, be apparent that the same portion of the ribbon must be used more than once in passing from the extreme left hand end 50 of the drum in Figure 2 to the right hand end, but the number of impressions thus made will not be sufficient to exhaust the ink of the ribbon.

By means about to be described, the paper ribbons R can be advanced through the guideway 75 and underneath the two longitudinally extending bars 100 and 101, which are spaced apart from each other as shown in Figure 5, and also vertically 55 spaced from the top of the supporting plate 102 which forms a cover for the water trough 103. At suitably spaced intervals, the plate 102 is provided with openings through which the felt disks 104 can project into the trough 103. These disks are

provided with axial extensions or smaller disks 105, which project over the portions of the supporting plate 102, which support the paper ribbons, and thus provide means for moistening the outer surfaces of the ribbons R which are preferably gummed. By providing means for moistening the outer side of the ribbons R, we make it possible to print on the un-gummed surface of the ribbon. The bar 101 is provided with a knife edge 106, which can be used in detaching the printed portion of the paper ribbon.

For advancing the paper ribbons through the corresponding guideways, we provide a plurality of friction rolls 110 which can be made of rubber or any other suitable material, and which are rotatably mounted upon the shaft 111, which extends longitudinally of the cover plate, and has suitable bearings in the two end portions of the cover plate. A lower friction disk 112 co-acts with each of the upper disks 110, and is provided with side flanges 113, to assist in guiding the ribbon. A ratchet 114 is secured to each of the disks 110 to rotate therewith, and during the return stroke of the platen is engaged by a pawl 115 which is pivoted at 116 to the rear end of the lever 86, and which is held in engagement with the ratchet 114 by the spring 117, which is coiled about the pin 116, and has one end bearing against the pawl 115, and the other end of which reacts against the upper edge of the lever 86. With this construction it will be seen that after a platen 87 has been moved downwardly to make an impression upon any given ribbon R, and is then released, the lever 86 will be returned to its normal position by the 105 spring 89, and at the same time the pawl 115 will engage the ratchet 114 to rotate the disk 110, which by co-acting with the disk 112 will cause the paper strip to be advanced through the guide-ways 75, and 110 between the bars 100 and 101, and the supporting plate 102, and project beyond the knife edge 106 in position to be torn off by the operator, and applied to the package 115 weighed.

The paper ribbons are torn from suitable supply rolls 120, (Fig. 4) which are supported by the sheet metal brackets 121, the lower ends of which are secured to a U-shaped channel 122 extending lengthwise of the machine by rivets 123, as shown in Figure 4, and to the upper ends of which are secured the U-shaped sheet metal members 124, the arms of which extend forwardly toward the front side of the machine. The rolls 120 are supported from the arms of the members 124 by means of the sheet metal hangers 125, the upper ends of which are flanged over as shown at 126 to be received in correspondingly shaped notches formed in the upper 125

edges of the arms of the U-shaped members 124. The lower ends of the hangers 125 have inclined slots 127 formed therein for receiving the spools 128, the heads 129 of which engage the outer sides of the hangers 125, and thus prevent the spools from being dislodged by movements in directions parallel with their axes. By thus supporting the spools of ribbon, they can be separately removed and replaced without interfering with the remaining ribbons. A cover 130 which is pivoted at 131 to the base portion of the casting can be swung rearwardly to permit access to the paper ribbons. In Figures 1 and 8, we have illustrated the means which we provide for supplying water to the trough 103. One end 135 of the housing has a chamber 136 formed therein, which is sealed by an air-tight closure 137. A channel 138 is formed in the housing, and leads downwardly from the bottom of the chamber 136 to a well 139, which communicates with the trough 103 through the conduit 140 formed integrally with the end well 135. The upper side of the well 139 is open to permit a finger to be inserted therein for closing the lower end of the channel 138. With the channel 138 thus closed, the chamber 136 can be filled with water and the closure 137 replaced to seal the upper end of the chamber 136. When the finger is then removed, water will run into the well 139, the conduit 140 and the trough 103, filling these receptacles until the level of the water in the well 139 reaches the lower end of the channel 138, when the flow of water will cease, and will be resumed only when water is drawn from the trough 103 by the moistening devices described above.

Having thus described the means by which the impressions corresponding to the type figures on the drum can be made, we shall next describe the means for determining the proper position of the drum for printing upon the proper strip a number indicating the proper charge to be made for any given package mailed to any given zone. For this purpose, we have herewith illustrated portions of a standard weighing mechanism comprising a platform 145 for receiving the packages to be weighed. This platform is supported by a post 146. (Fig. 3) the lower end of which is supported by and pivotally secured to the lever 147, by the hollow pin 148. The lever 147 has one end pivotally mounted upon the pin 149. A link 150 is pivotally supported upon the pin 151, and its opposite end is connected with the upper end of the post 146 by a pivotal connection 152. The length of the link 150 is equal to the distance between the pivot pins 148 and 149 so as to cause the post 146 to move up and down in a vertical direction.

The free end of the lever 147 is provided with an arcuate surface 147^a for co-acting with the strap 147^b, the lower end of which is secured to the lower end of the arcuate surface 147^a by a screw 147^c, and the upper end of which is secured to a yoke 152, which is supported by the straps 153 and 154, which are respectively wrapped about and supported by the cams 155 and 156, the ends of the straps being secured to these cams by the screws 157 and 158 respectively. These cams are rigidly secured to the shafts 159 and 160 respectively, to which are also secured the smaller cams 161 and 162 respectively. The shafts 159 and 160 are rotatably mounted in the opposite ends of a second yoke formed by the bars 163 and 164, (see Figs. 4 and 7) between the respective ends of which the two sets of cams referred to above are respectively mounted. This yoke surrounds a frame comprising the vertical side members 165 and 166, and the cross bars 167 and 168. The latter bar comprises two lateral extensions from the bearing 17 which is supported by the pedestal 18 and supports the two vertical side members 165 and 166. Two straps 169 and 170 have their upper ends secured to the upper ends of the vertical side members 169 and 170 by the screws 171 and 172 respectively, and their lower ends secured to the lower ends of the cams 161 and 162 respectively by the screws 173 and 174 respectively.

The lever 147 is balanced by a suitable adjustable counterweight 175, and the two shafts 159 and 160 are also provided with adjustable counterweights 177 and 178 respectively.

The weighing mechanism described above embodies certain modifications of a standard weighing mechanism to adapt it to the purpose at hand, and will give approximately equal increments in deflection for equal increments in load, although this is not a necessary requirement for the construction and proper operation of our improved mechanism, as it can be equally well adapted to the use of a weighing mechanism in which the movements throughout the entire range of the mechanism are not uniform for equal increments in loads.

The bar 164 (Fig. 4) comprises two bifurcations 164' and 164'' in which the pin 180 rotates. The lever 181 extends between these two bifurcations, and has one end secured to the pin 180 by means of a pin 182. Projecting downwardly and inwardly from the lower side of the lever 181 is a pawl 183, which is adapted to engage the teeth of the spiral ratchet 184, the number of teeth on the spiral ratchet corresponding in number to the number of type figures in each of the rows 11, so that for each advance of one tooth of the spiral ratchet, the drum will be advanced to bring the next set of type figures beneath the platen. Since the inner teeth of the spiral ratchet are nearer the

axis of the drum 10 than the outer teeth, this means that the length of the teeth must increase from the inner end of the spiral to the outer end thereof, as shown in 5 Figure 4. We have illustrated these teeth as being of substantially the same height, because, as described above, the weighing mechanism will give substantially equal increments in deflection for equal increments 10 in load.

The lever 181 is yieldingly urged toward the bar 164 by the leaf spring 185, one end of which is secured to the bar 164 by suitable rivets 186, and the other end of which engages a projection 187 extending upwardly 15 from the lever proper. In this manner, the pawl 183 is yieldingly urged toward a position for engaging one of the teeth of the ratchet 184, the particular tooth of which is thus engaged being determined by the vertical position of the pawl 183, which in turn is determined by the weight imposed upon the platform 145. The projection 187 also acts as a stop to limit the inward movement 20 of the pawl 183 under the tension of the 25 spring 185.

The pawl 183 is normally held out of the path of the teeth of the ratchet 184 by the engagement between the lower end of the 30 link 190 with the laterally offset portion 191 (see Figure 7) of the free end of the lever 181. The link 190 is supported by the two links 192 and 193, (Fig. 2) which are pivotally connected at 194 and 195 with the 35 link. The other ends of the links 192 and 193 are pivotally secured to the vertical side member 165 by the screws 195 and 196. (See Figure 2). The pressure of the spring 185 against the projection 187, and the resulting pressure of the end of the lever 40 upon the link 190 tends to push the link 190 inwardly and thus cause it to move upwardly on its pivot points. The tension of the spring 181 is assisted by the tension 45 of the spring 197, one end of which is secured to the upper end of the link 190, and the upper end of which is secured to the vertical frame 165, at 198. The upward movement of the link 190 is, however, resisted by the pressure of the end of the rod 50 199, (Fig. 4) which rests upon the upper end of a latch 200, which is pivotally mounted upon a projection 201 extending from the upper end of the link 190 by the pin 202. The rod 199 is secured to the free ends of 55 the two links 203 and 204 (Figs. 4 and 5) which are respectively pivotally mounted upon the end members of the cover plate by the screws 205 and 206 respectively. A 60 coiled spring 207 interposed between the top of the cover plate and the link 204 pushes the rod 199 downwardly with sufficient force to overcome the lifting tendencies upon the link 190 of the spring 185 and 197.

65 For releasing the latch 200 from the rod

199 to permit the link 190 to move upwardly and laterally inwardly so as to cause the pawl 183 to be positioned in the path of the tooth of the ratchet 184, we provide a 70 release key 210 which is supported by the vertical link 211 (see Figure 4). The lower end of the link 211 is pivotally secured to one end of the bell crank lever comprising the two arms 212 and 213 by means of a pin 214. The bell crank lever is pivotally 75 mounted upon the flange 71 of the supporting plate 70 by means of a screw 216. The upper end of the arm 213 is connected by a link 217 with an intermediate portion of the latch 200. A spring 218, one end of 80 which is secured to the link 217, and the other end of which is secured to the flange 71, yieldingly holds the latch in a vertical position, and at the same time holds the release key 210 in its uppermost position. 85 When the release key 210 is depressed, the latch 200 is withdrawn from beneath the end of the rod 199, which projects through a slot 219 in the flange 71, and thus permits the springs 185, and 197 to move the link 190 90 upwardly and laterally inwardly thereby causing the pawl 183 to be moved under the tension of the spring 185 into the path of the teeth of the ratchet 184. Continued 95 downward movement of the release key 210 next causes the latch 220 which forms an extension of the bell crank lever to be released from the stop 221, whereupon the drum rotates in a counterclockwise direction (see Figure 4) under the influence of the spring 28, until the pawl 183 is engaged by one of the teeth of the ratchet 184 whereupon the drum comes to rest at a position determined by the weight of the object 100 placed upon the platform 145.

Upon the release of the key 210, the spring 218 will cause the latch 200 to move into a position extending above the rod 199 thereby holding the link 190 in its raised position. After the proper printing position of the drum 10 has been determined as described above, the operator will strike the key 88 corresponding to the zone to which the package is to be shipped, thereby causing an indication of the proper postal charge 110 to be impressed upon the paper ribbons corresponding to the key pressed. From an inspection of Figure 5 it will be noted that the upper edge of the inner ends of all of the levers 86 engage the lower side of the rod 199. Consequently, when any one of the keys 88 is depressed, the rod 199 will be raised, thereby pushing the latch 200 laterally out of the path of the rod 199, and permitting it to return beneath the rod 199 115 under the influence of the spring 218. Upon the release of the key 88 after the printing stroke has been made, the spring 207 will force the rod 199 downwardly against the upper end of the latch 200, thereby moving 120 125 130

the link 190 downwardly and outwardly into engagement with the offset end 191 of the lever 181, thus moving the pawl 183 out of engagement with the tooth of the ratchet 184 whereupon the drum will resume its rotation under the tension of the spring 28, and rotate until the stop 221 is re-engaged by the latch 220, which upon the release of the key 210 is again moved into the path of the stop 221 through the action of the spring 218. The operator then tears off the printed portion of the ribbon which has been projected from the machine in the manner described above, and may attach it to the package to indicate the proper postal charge for this package. It will, of course, be understood that if our improved mechanism is merely to be used as an indicating device, the printing mechanism described can be omitted, and the drum will then assume the form of a dial, the numbers of which could be observed through a suitable slot formed in the housing of the machine.

While we have described the details of construction of the preferred embodiment of our improved weighing mechanism, it is to be clearly understood that it is not limited to these details of construction, but is capable of other adaptations and modifications within the scope of the appended claims. It is to be further understood that although we have described our invention as applied to the determination of the proper charges to be made for mailing a package to any one of the different postal zones, this adaptation is merely illustrative, and that our invention may be used wherever it is desired to determine quantities or values which depend upon two different variables.

Having thus described our invention, what we claim is:

1. The combination with a drum having a plurality of rows of figures corresponding in number to the number of postal zones and extending circumferentially thereof, the figures of each row being arranged in ascending values corresponding to the postal charges for a given zone, the zero position of all of said rows lying in a line extending longitudinally of said drum, of a motor located inside said drum for rotating said drum, guide means for each of said rows of type figures for guiding a paper ribbon to a printing position over each of said rows, the said guide means extending transversely of said drum, an inking ribbon, means actuated by said drum for intermittently advancing said inking ribbon transversely of said paper ribbons, a platen for co-acting with the type of each row of type figures to cause said ribbon to make printed impressions on said paper ribbons, a support mounted over said drum, a lever for actuating each of said platens, said levers being pivotally mounted on said support, and means actuated by each of said levers for advancing the corresponding paper ribbon through its guideway, a spiral ratchet carried by one end of said drum, a weighing mechanism comprising a stop movable proportionately to the weight imposed on said weighing mechanism for engaging the teeth of said ratchet to determine the printing position of said drum, releasable means for holding said drum in its zero position, and means actuated by any one of said levers during its return stroke for releasing said stop from said ratchet and permitting said drum to move to its zero position.

2. The combination with a drum having a plurality of rows of figures corresponding in number to the number of postal zones and extending circumferentially thereof, the figures of each row being arranged in ascending values corresponding to the postal charges for a given zone, the zero position of all of said rows lying in a line extending longitudinally of said drum, of a motor for rotating said drum, guide means for each of said rows of type figures for guiding a paper ribbon to a printing position over each of said rows, the said guide means extending transversely of said drum, an inking ribbon, means for intermittently advancing said inking ribbon transversely of said paper ribbons, a platen for co-acting with the type of each row of type figures to cause said ribbon to make printed impressions on said paper ribbons, a support mounted over said drum, a lever for actuating each of said platens, said levers being pivotally mounted on said support, and means actuated by each of said levers for advancing the corresponding paper ribbon through its guideway, a spiral ratchet carried by one end of said drum, a weighing mechanism comprising a stop movable proportionately to the weight imposed on said weighing mechanism for engaging the teeth of said ratchet to determine the printing position of said drum, releasable means for holding said drum in its zero position, and means actuated by any one of said levers during its return stroke for releasing said stop from said ratchet and permitting said drum to move to its zero position.

3. The combination with a drum having a plurality of rows of figures corresponding in number to the number of postal zones and extending circumferentially thereof, the figures of each row being arranged in ascending values corresponding to the postal charges for a given zone, of means for rotating said drum, guide means for each of said rows of type figures for guiding a paper ribbon to a printing position over each of said rows, the said guide means extending

- transversely of said drum, an inking ribbon, means for intermittently advancing said inking ribbon transversely of said paper ribbons, a platen for co-acting with
- 5 the type of each row of type figures to cause said ribbon to make printed impressions on said paper ribbons, a support mounted over said drum, a lever for actuating each of said platens, said levers being pivotally mounted on said support, and means actuated by each of said levers for advancing the corresponding paper ribbon through its guideway, a ratchet connected with said drum, a weighing mechanism comprising a
- 10 stop movable proportionately to the weight imposed on said weighing mechanism for engaging the teeth of said ratchet to determine the printing position of said drum, releasable means for holding said drum in its zero position, and means actuated by any one of said levers during its return stroke for releasing said stop from said ratchet and permitting said drum to move to its zero position.
- 15 4. The combination with a drum having a plurality of rows of figures corresponding in number to the number of postal zones and extending circumferentially thereof, the figures of each row being arranged in ascending values corresponding to the postal charges for a given zone, of means for rotating said drum, guide means for each of said rows of type figures for guiding a paper ribbon to a printing position over each of said rows, the said guide means extending transversely of said drum, an inking ribbon, means for intermittently advancing said inking ribbon transversely of said paper ribbons, a platen for co-acting with the type
- 20 of each row of type figures to cause said ribbon to make printed impressions on said paper ribbons, a lever for actuating each of said platens, and means actuated by each of said levers for advancing the corresponding paper ribbon through its guideway, a ratchet connected with said drum, a weighing mechanism comprising a stop movable proportionately to the weight imposed on said weighing mechanism for engaging the teeth of said ratchet to determine the printing position of said drum, releasable means for holding said drum in its zero position, and common means for releasing said stop from said ratchet and permitting said drum to move to its zero position.
- 25 5. The combination with a drum having a plurality of rows of figures corresponding in number to the number of postal zones and extending circumferentially thereof, the figures of each row being arranged in ascending values corresponding to the postal charges for a given zone, of means for rotating said drum, guide means for each of said rows of type figures for guiding a paper ribbon to a printing position over each of said rows, the said guide means extending transversely of said drum, an inking ribbon, means for intermittently advancing said inking ribbon transversely of said paper ribbons, a platen for co-acting with the type
- 30 of each row of type figures to cause said ribbon to make printed impressions on said paper ribbons, a lever for actuating each of said platens, and means actuated by each of said levers for advancing the corresponding paper ribbon through its guideway, a ratchet connected with said drum, a weighing mechanism comprising a stop movable proportionately to the weight imposed on said weighing mechanism for engaging the teeth of said ratchet to determine the printing position of said drum, releasable means for holding said drum in its zero position, and common means for releasing said stop from said ratchet and permitting said drum to move to its zero position.
- 35 6. The combination with a drum having a plurality of rows of figures corresponding in number to the number of postal zones and extending circumferentially thereof, the figures of each row being arranged in ascending values corresponding to the postal charges for a given zone, of means for rotating said drum, guide means for each of said rows of type figures for guiding a paper ribbon to a printing position over each of said rows, the said guide means extending transversely of said drum, a platen for co-acting with the type of each row of type figures to make printed impressions on said paper ribbons, means for actuating each of said platens, and means for advancing each of said paper ribbons through its guideway, a weighing mechanism, means for releasing said drum to permit it to rotate, and means controlled by said weighing mechanism for determining the printing position of said
- 40 drum.
6. The combination with a drum having a plurality of rows of type figures corresponding in number to the number of postal zones and extending circumferentially thereof, the figures of each row being arranged in ascending values corresponding to the postal charges for a given zone, of means adjacent each row for guiding a paper strip into printing position, means for co-acting with each row of figures for making printed impressions on its associated paper strip, means for rotating said drum and paper strip guiding means relatively to each other, and means actuated by the weight of an object for controlling said last named means.
7. In a computing mechanism, the combination with a drum having rows of indicia, each row arranged circumferentially in ascending values corresponding to the computed charges for any given factor, of means for rotating said drum in a continuous direction, means for holding said drum when it returns to a normal position, a weighing mechanism, cooperating means on said drum and said weighing mechanism for determining, by the weight of an object on said weighing mechanism, the position of said drum, a release for said holding means allowing said drum to rotate to said determined position, the release of said cooperating means allowing said drum to return to said normal position, and an index which cooperates with said indicia for giving computed charges.
8. The combination with a drum having a row of type figures arranged in ascending values corresponding to the postal charges for a given zone, of means for guiding a paper strip into position to receive an impression from said type figures, means actuated by, and proportionately to, the weight of an object for determining the relative positions of said drum and guiding means, and power means for rotating said guiding means and said drum relatively to each other in a continuous direction.
9. The combination with a printing mechanism having type for printing numbers corresponding to the various postal charges for a given postal zone on a piece of paper, of a weighing mechanism comprising a stop movable in proportion to the weight imposed on said weighing mechanism, and

means movable in a continuous direction and controlled by said stop for positioning the proper type in printing relation with said pieces of paper.

- 5 10. The combination with a drum having a row of type figures extending circumferentially thereof and arranged in ascending values corresponding to the charges for any given zone, of a platen for co-acting with 70
10 said type figures, means for guiding a paper ribbon between said platen and said type figures, common means for actuating said platen and advancing said paper strip in said guideway, means for rotating said 75
15 drum, weighing means comprising an element for determining the amount of rotation of said drum, and means actuated by said platen actuating means for releasing said drum from the control of said element.
20 11. The combination with a drum having a row of type figures extending circumferentially thereof and arranged in ascending values corresponding to the charges for any given zone, of a platen for co-acting with 80
25 said type figures, means for guiding a paper ribbon between said platen and said type figures, means for actuating said platen, and means for rotating said drum, weighing 85
30 means comprising an element for determining the amount of rotation of said drum, and means for releasing said drum from the control of said element.

- 35 12. The combination of a set of type corresponding to values determined by two variable factors one of which is weight, means for holding a piece of paper in printing relation to said type, a plurality of platens corresponding to the other of said factors each, when actuated, co-operating with said 100
40 type to print indicia of one of said values on said paper, means for moving said type in a continuous direction relative to said paper, a weighing mechanism, a stop controlled by said weighing mechanism for 105
45 limiting said relative movement of said type to present in said printing relation type of values corresponding to the weight of an object on said weighing mechanism, and means for selectively actuating one of 50
55 said platens to print on said paper the indicia of a value corresponding to the weight of said object and to said other factor.

- 55 13. The combination of a set of type corresponding to values determined by two variable factors one of which is weight, means for holding a piece of paper in printing relation to said type, a plurality of platens corresponding to the other of said factors, each, when actuated, cooperating with said 110
60 type to print indicia of one of said values on said paper, means for moving said type relative to said paper in a continuous direction, a stop for stopping said type at its 115
65 normal position, a release for said stop, a weighing mechanism, cooperating means on

said mechanism and said set of type for limiting said relative movement of said type to present in printing relation type of values corresponding to the weight of an object on said mechanism, said co-operating 70
75 means comprising a ratchet and a stop adapted to contact with said ratchet, and means for selectively actuating one of said platens to print on said paper the indicia of a value corresponding to the weight of said object and to said other factor, the release of the first-mentioned stop permitting said type to move relatively to said paper to the position determined by said cooperating means, and the release of said cooperating 80
85 means permitting said type to move relatively to said paper to said normal position.

14. The combination of a set of type corresponding to values determined by two variable factors, one of which is weight, means 85
85 for holding a plurality of pieces of paper in printing relation to said type, a plurality of platens, each of said platens being associated with one of said pieces of paper, and each, when actuated, cooperating with said 90 type to print indicia of one of said values on its associated piece of paper, means controlled by the movement of each of said platens to eject a length of its said associated paper, means for moving said type relatively to said paper, a weighing mechanism, cooperating means on said mechanism and said set of type for limiting said relative movement of said type to present in printing relation type of values corresponding to the weight of an object on said mechanism, said cooperating means comprising a ratchet and a stop adapted to contact with said ratchet, and means for selectively actuating one of said platens to print on its said associated paper the indicia of a value corresponding to the weight of said object and to said other factor. 100
105

15. The combination with a drum having a row of type figures extending circumferentially thereof and arranged in ascending values corresponding to the charges for any given zone, of a platen for co-acting with 110
115 said type figures, means for guiding a paper ribbon between said platen and said type figures, common means for actuating said platen and advancing said paper strip in said guideway, means for rotating said drum, a weighing mechanism, means for determining the amount of rotation of said 120
125 drum, said last mentioned means comprising a co-operating ratchet and stop, one of which is on said weighing mechanism, and the other of which is on said drum, and means actuated by said platen actuating means for releasing said drum from the control of said determining means.

16. The combination with a drum having a plurality of rows of type figures extending circumferentially thereof each row ar- 130

ranged in ascending values corresponding to the computed charges for a given rate, of a plurality of platens for co-acting with said type figures, means for guiding a plurality of paper ribbons between said platens and said type figures, means for selectively actuating said platens, means for rotating said drum, a ratchet on said drum, weighing means comprising a stop contacting with said 10 ratchet for determining the amount of rotation of said drum, and means for releasing said drum from the control of said element.

In witness whereof we hereunto subscribe our names as follows:

St. Louis, Missouri, February 14th, 1921.
FRANK B. MULFORD.

Witnesses:

H. P. RUEWAR,
F. C. HOTFELDER.

Chicago, Illinois, February 15th, 1921.
JOHN DAVID DICKINSON.

Witnesses:

ALBIN C. AHLBERG,
OLIVER H. PARMELEE.
